H. G. PAPE,
HOLDING MEANS FOR HOUSINGS,
APPLICATION FILED JUNE 23, 1916.

1,216,598.

Patented Feb. 20, 1917.

Inventor:
Herman G. Pape

By George A. Rockwell,
Atty.

UNITED STATES PATENT OFFICE.

HERMAN G. PAPE, OF NEW YORK, N. Y., ASSIGNOR TO RALPH A. SCHOENBERG, OF NEW YORK, N. Y.

HOLDING MEANS FOR HOUSINGS.

1,216,598.

Specification of Letters Patent. Patented Feb. 20, 1917.

Application filed June 23, 1916. Serial No. 105,512.

To all whom it may concern:

Be it known that I, HERMAN G. PAPE, of New York, in the county and State of New York, have invented new and useful Holding Means for Housings, of which the following is a specification.

Heretofore the means for holding or latching together the parts of metal housings have comprised rivets or other devices 10 which frequently tear through the metal wall of the housing member, because of the thinness of the metal usually employed in making the latter.

The main object of my invention is to 15 overcome this and other defects and to provide efficient, simple and cheap means for holding together parts of housings especially metal housings and I have in mind as 20 particular embodiments the metal shells of electrical apparatus such as lamp sockets, switches and the like although my invention is not by any means limited to these.

One feature of my invention is a housing member having two openings and with a 25 holding member attached to said housing member, said holding member having two projections secured within said openings to fasten said holding member to the housing member.

Another feature consists in bending or upsetting the ends of said projections so as to engage the housing member to fasten the holding member thereto.

Another feature consists in rounding one 35 edge of said holding member so as better to accomplish the latching of the parts of the housing.

Another feature consists in making the holding member from sheet metal.

40 In the accompanying drawings:—

Figure 1 is an elevation, partly in section, of a lamp socket housing embodying my invention;

Fig. 2 is a plan view, partly in section, 45 of the body section of the lamp socket housing shown in Fig. 1;

Fig. 3 is an elevation of the cap section of the housing shown in Fig. 1;

Fig. 4 is an elevation of the body section 50 of the housing shown in Fig. 1;

Fig. 5 is a plan view of the stud hereinafter referred to; and

Fig. 6 is an elevation of a pendent switch having a housing made in accordance with 55 this invention.

Having reference to the drawings, 1 represents the body section of a lamp socket housing and 2 the cap section, said two sections fitting together telescopically in the usual fashion and being used as a housing 60 for the other parts, not shown, of the socket.

In accordance with my invention the flange or skirt 3 of the cap section 2 is made with a pair of oppositely disposed slots 4 adapted to interlock with a pair of oppositely disposed holding lugs 5, 5 provided upon the body section 1 near one end of the latter.

The body section 1 is, as usual, formed with a key receiving slot 6 and one of the holding lugs 5 is placed adjacent said slot so that when it is desired to remove the cap section 2 the corner 7 to which one of the lugs 5 is secured can be pressed inwardly thus withdrawing said lug from its slot 75 and permitting the cap section 2 to be removed from the body section.

The cap section 2 is applied to body section 1 by sliding it down onto the end of said body section, the edge of the skirt 3 80 sliding over rounded or beveled surfaces 8 provided on the lugs 5 and at the same time flexing the corner 7 inwardly until the lugs 5 reach and enter the slots 4 whereupon the corner 7 springs outwardly leaving the two 85 sections locked together.

Heretofore it has been customary to provide the body section 1 with two lugs but almost invariably such lugs have been in the form of simple rivets, each extending 90 through a simple hole in the body section and upset at its inner end to fasten it in place. As a result the sidewise pressures and strains imposed thereon while the housing was in use and particularly while the cap 95 section was being applied to or removed from the body section, acted to flex the metal of body section 1 adjacent the rivet stud and cause the rivet stud to work loose and become detached. This was due in part to the character of stud employed, and the method of connecting it to the body section, but also to the fact that socket shells are commonly made from very thin sheet metal and it is impossible to securely fasten an ordinary 105 stud thereto by a single riveted joint located at a single point.

To obviate these objections I make each stud 5 in the form of a staple having two legs 9 connected by an intermediate body portion 110

10. Two separate holes are provided in housing section 1 at 11 and 12 for each stud 5 and after legs 9 of the stud have been inserted in said holes from the outside, the inner ends of legs 9 are upset or bent over against section 1 thus permanently fastening the stud in place with the body 10 thereof in contact with the outer side of said section.

This construction not only distributes the 10 strains and stresses upon a plurality of joints but the wall of the housing between said joints backs up and supports the stud thus relieving the two joints to a material extent.

15 The staple shaped stud 5 above described may be produced in any desired manner, but I prefer to stamp the same out of sheet metal because the means employed with this method can be made to produce the rounded or beveled surface 8 at the same time that the staple is cut from the sheet metal.

In Fig. 6 I have shown a pendent switch having a housing comprising a body section

1^a provided with one or more studs 5 and a removable cap section 2^a formed with one or 25 more slots 4 coöperating therewith.

What I claim is:

1. A device of the character described comprising a housing member having two openings in its wall, which wall extends 30 from one of said openings to the other; and a holding member having two legs to enter said openings and having a body portion projecting from said wall to a substantial extent and engaging said wall at substantially all points between said openings.

2. A device of the character described comprising a housing member having two openings and a holding member having an 40 elongated body extending crosswise of the axis of said housing member and having two legs in said openings, said body engaging said housing member at substantially all points between said openings.

HERMAN G. PAPE.
